UNITED STATES PATENT OFFICE.

JOHN A. MCKIBBEN, OF STERRETT, INDIAN TERRITORY.

DESIGN FOR A CISTERNS-CASING.

SPECIFICATION forming part of Design No. 34,441, dated April 30, 1901.

Application filed March 18, 1901. Serial No. 51,795. Term of patent 14 years.

To all whom it may concern:

Be it known that I, JOHN A. MCKIBBEN, a citizen of the United States, and a resident of Sterrett, in the county of Blue, Indian Territory, have invented and produced a new and original Design for Cistern-Casings, of which the following is a specification.

Figure 1 is a perspective view of the cistern-casing, showing my new design. Fig. 2 is a central vertical section of the casing. Fig. 3 is a top plan view of the casing. Fig. 4 is a transverse horizontal section taken on line *a b* of Fig. 1.

The central and vertical portion 3 of the casing is cylindrical, as shown. The upper portion of the casing converges obliquely to a relatively small neck 4. The upper portion of this neck 4 expands into an annular substantially level flange or curb 5, the outline of which is circular, as shown. A concentric circular opening 7 is formed in the flange 5 and communicates with the interior of the

neck 4. 6 designates a shouldered annular recess formed in the upper face of the curb 5, concentrically with the opening 7 and the periphery of the curb 5. The upper face of said curb or flange is slightly inclined downward from the shouldered recess to the periphery thereof, as shown in Fig. 2. The lower portion of the casing below the cylindrical portion 3 converges to a relatively small bottom 8, which is approximately cylindrical in form.

Having now described my design, what I claim as new, and desire to secure by Letters Patent of the United States, is—

The design for a cistern-casing, substantially as herein shown and described.

In testimony whereof I affix my signature in the presence of two witnesses.

JOHN A. MCKIBBEN.

Witnesses:

J. W. DUNCAN,
J. W. SCEARCE.
